INKSTAND

Gustav J. Sengbusch, Milwaukee, Wis.

Application September 28, 1942, Serial No. 459,932

5 Claims. (Cl. 120—59)

This invention relates to improvements in the construction of inkstands and it has particular reference to the construction of inkstands of the kind which embody a pen dipping well, preferably having a pen supporting socket associated with the well, and an ink supply reservoir or chamber connected to the pen dipping well in such a manner as to maintain a constant depth of ink in the pen dipping well.

The main object of the invention is to provide an inkstand of the character indicated in which the flow of ink from the reservoir to the pen dipping well will be effectively maintained and controlled and in general, it is the object of the invention to provide an improved device of the character indicated. The device is of such a construction that it may be made economically and at low cost so that the device may be sold at a low price.

Other objects and advantages of the invention will be understood by reference to the following specification and accompanying drawing, wherein there is illustrated an inkstand embodying a selected form of the invention.

In the drawing, Fig. 1 is a perspective; Fig. 2 is a section on a vertical plane, extending through the pen dipping well and ink reservoir at approximately the longitudinal center of the device; Fig. 3 is a top plan of the base part of the device, other elements being removed; and Figure 4 is a perspective of an ink feeding cap forming part of the ink reservoir.

The improved inkstand herein disclosed comprises a base 5, preferably molded of glass. The base is so formed as to provide a pen dipping well 6 and a chamber or receptacle 7 for receiving an ink bottle or reservoir 8.

In the present instance, the ink bottle 8 is illustrated as being of round form, having a more or less domed top 9 and an externally screw threaded mouth portion 10. The ink bottle 8 is also preferably molded of glass, the threads on the mouth portion 10 being formed in the molding operation. The bottle is also preferably formed with an outwardly extending flange or shoulder forming a rib 11 intermediate its ends.

For receiving the ink bottle 8, the chamber 7 in the base is made circular to substantially conform to the outside shape of the portion of the ink bottle below the rib 11 thereof. The wall 12 of the chamber 7 in the base extends above the top surface 13 of the base proper so that said chamber is formed to extend partially above the base 5 and partially into the base 5.

The chamber 7 is connected to the pen dipping

well 6 through a slot or opening 14 provided in the wall of the chamber 7, said slot 14 extending from top to bottom of the wall forming the chamber 7 and to the bottom 15 of the pen dipping well 6. The chamber 7 is provided with a stepped bottom arrangement, providing a recessed bottom 16 in the same plane as the bottom 15 of the pen dipping well and a main bottom wall 17 stepped upwardly from the recessed bottom 16.

10 The ink bottle 8 is positioned by having its rib 11 seat on the upper edge of the chamber wall 12, as clearly shown in Fig. 2 and the portion of the bottle which enters the chamber is of such size as to fit freely therein. To prevent rotation of the bottle 8, it may be provided with a lug 18 which enters the slot 14 as clearly shown.

15 The mouth end of the ink bottle 8 is provided with a cap 19, which may be formed of any suitable material which is not corroded or otherwise adversely affected by ink. The cap may, for example, be made of glass, porcelain or other ceramic material, certain fibrous or plastic material compositions, and when available, rubber may be employed.

20 The cap 19 is also molded and it is formed with a downwardly extending dome 20 having a slot-like-opening 21 formed therein as a part of the molding operation. Suitable screw threading may also be formed in the cap for cooperation with the external screw threading on the mouth end portion of the ink bottle for detachably securing the cap to the bottle.

25 When the cap is made of rubber or any other material having an adequate degree of resiliency, it may be advantageously provided near its upper end with an outwardly extending fin 22, which will frictionally bear against the wall of the chamber 7 as shown. Such a fin is desirable in that it frictionally connects the ink bottle to the base and resists unintentional removal of the ink bottle from the base as might happen, for example, in the event that an attempt is made to lift the ink stand by grasping the ink bottle portion thereof. Said fin is not, however, an essential element of the inkstand. To further assist in positioning the ink bottle in the receptacle 7, the cap 19 may have a series of circumferentially spaced ribs 23 formed on its outer surface, said ribs being of such size that the cap will fit snugly in the chamber 7. The ribs 23 like the fin 22 are not essential elements of the structure.

30 The slot 21 is of such small size that some assistance may be required to effect the flow of ink outwardly therethrough. In order to insure the proper flow of ink through the slot 21, the

recessed bottom 16 of the chamber is provided with a small knob or boss 24, which projects into close proximity to the lowermost portion of the slot. When the ink bottle 8 is in its normal inverted position as shown in Fig. 2, there will be a normal tendency for ink to pass through the slot 21. However, because of the small size thereof, the ink may not flow freely but will tend to hang from the lower end of the slot 21 without actually flowing therefrom. The ink will, however, bulge downwardly from the slot 21 to such an extent that it will contact the surface of the knob 24 whereupon a flow of ink will be established until the ink fills the recessed portion 25 of the chamber and substantially closes the slot 21. The ink will, of course, flow through the opening 14 into the pen dipping well 6 to approximately the same depth.

Because of changes in barometric pressure, ink will sometimes be caused to flow out of the ink bottle to such an extent to increase the depth of ink in the recess 25, whereupon the ink will flow over the bottom wall 17, which then acts as the bottom of an overflow chamber surrounding the recess 25. By such overflow provisions, the depth to which the ink will be discharged into the recess 25 and pen dipping well 6 will vary only slightly.

To partially close the slot 14, there is provided a wedge shaped piece of material indicated at 26, same being of such size as to fit in the slot 14 from immediately below the bottom of the lug 18 of the ink bottle to approximately the ink level maintained in the pen dipping well.

The member 26 may be formed of any suitable fibrous or plastic material composition, or other material which resists corrosion by ink, and the side edges of such insert piece may be coated with a bituminous or like adhesive material, which will tend to adhesively secure the member in place. The use of such adhesive is not, however, of importance since any wedge shaped piece of material will have a normal tendency to be wedged in place in the slot 14, such wedging action being normally adequate for the purpose indicated. To facilitate positioning of the member 26, the ends of the wall 12 which form the slot 14 may be provided with spaced riblike formations 27 and 28, which cooperate to form a guideway for receiving the member 26 in a substantially fixed position.

The pen holder or socket 29 molded of porcelain or other suitable material, may be positioned in the pen dipping well 6 and may be so formed as to be adapted to hold a pen in upwardly extending readily available position. The socket element 29 may conveniently have its lower portion 30 of substantially cylindrical formation and it may be seated in the pen dipping well 6 and frictionally held therein by means of a suitable band 31 of fiber or other material.

The opening in the socket 29 through which the pen enters the pen dipping well preferably has an internal formation such as shown in my Patent 2,188,962 and it is preferably so formed that when a pen is seated therein, the lower end portion of the pen point will at least partially be immersed in ink, some of which will then be carried upwardly on the pen point by capillary action between the face of the pen point and the adjacent wall of the pen receiving socket.

The bottom of the base member 5 may be recessed as indicated at 32 to conform with the formation of the various chambers and recep-

tacles in the base, thereby to reduce the amount of material required to form the base.

In one practical embodiment of the described structure, the ink bottle 8 and the base 5 are made of glass and the cap 19 and pen socket 29 are made of porcelain, and the closure member 26 is made of a fibrous composition material. All of the materials employed are readily available in adequate quantities, none of them being characterized as essential defense or war materials. The formation of the base with the opening 14 connecting the ink reservoir with the pen dipping well in the manner explained is a matter of convenience and practicality in manufacturing operations. The inserted closure element serves, of course, to retard evaporation and to exclude dust and foreign matter. The insert closure 26, the pen socket 29 and the cap 19 may be finished in any desired color to harmonize or contrast with the glass parts. If the glass parts are made of clear glass, the finish on the cap 19 will be visible through the glass wall surrounding it. The general appearance of the device may, to some extent, be controlled by the finish employed on the outside of the cap 19, the insert closure 26 and the socket 29.

Changes in the described structure may be made without departing from the spirit of the invention, the scope of which should be determined by reference to the following claims, the same being construed as broadly as possible consistent with the state of the art.

I claim:

1. An inkstand comprising a base having a pen dipping well and a reservoir chamber, said well and chamber being interconnected to permit the flow of ink from said chamber to said well, and an ink bottle adapted to be seated on said base and to project into said chamber, and being provided with a depending dome having an ink discharging opening of such size as of itself to prevent the free flow of ink outwardly therethrough but to allow the ink to bulge outwardly, the bottom of said chamber having an upwardly projecting knob having an external surface portion in such proximity to said opening as to be engaged by ink protruding from said opening to thereby establish the flow of ink through the opening when the ink bottle is in operative position.

2. An inkstand according to claim one wherein the ink bottle is provided with a removable cap having said dome and discharge opening therein, and which cap is provided with an outwardly extending fin for frictionally engaging the wall of said chamber to thereby frictionally connect the ink bottle to the base.

3. An inkstand of class described comprising a base having a pen dipping well and an ink reservoir chamber spaced from said well, said base structure having a slot for establishing communication between said well and chamber, and a closure element seated in said slot but spaced upwardly from the bottom thereof so as to leave under said closure, a passageway connecting said chamber and well.

4. An inkstand of class described comprising a base having a pen dipping well and an ink reservoir chamber spaced from said well, said base structure having a slot for establishing communication between said well and chamber, and a closure element seated in said slot but spaced upwardly from the bottom thereof so as to leave under said closure, a passageway connecting said chamber and well, the wall portions of the base

forming the sides of said slot being provided with relatively spaced ribs forming guideways for positioning said closure element in said slot.

5. An inkstand comprising a base having a pen dipping well and a chamber, said base having an upstanding wall portion forming the upper portion of said chamber, said well and chamber being interconnected to permit the flow of ink from said chamber to said well, an axially vertical ink bottle having a substantially parallel walled body portion provided with a closure at

its upper end and terminating at its lower end in an unconstricted mouth portion, said bottle having an outwardly extending flange intermediate its ends and being positioned on said base with its mouth end portion projecting into said chamber, said flange engaging the upper end of said chamber forming wall portion of the base to thereby support the bottle, and means for controlling the discharge of ink from the mouth of said bottle into said chamber.

GUSTAV J. SENGBUSCH.
